DISPENSING AND PACKAGING DEVICE FOR FLUIDS

Original Filed Jan. 11, 1936

Inventor:
Martin C. Schwab.
By: Paul Carpenter
Atty.

UNITED STATES PATENT OFFICE

2,248,127

DISPENSING AND PACKAGING DEVICE FOR FLUIDS

Martin C. Schwab, Chicago, Ill.

Original application January 11, 1936, Serial No. 58,649. Divided and this application April 20, 1939, Serial No. 268,904

1 Claim. (Cl. 128—214)

This invention relates to liquid dispensing apparatus of the general character referred to in my patents numbered 2,010,417, granted August 6, 1935, and 2,065,829, granted December 29, 1936, and is directed to certain improvements thereover. The present application is a division of my copending application Serial No. 58,649, filed January 11, 1936.

This invention is particularly directed to the provision of liquid dispensing apparatus having certain advantages over my aforementioned patents in that the dispensing assembly and container may be merchandized as a unitary assembly, requiring the minimum amount of handling to put the same to use.

In my patents aforementioned, the dispensing apparatus and container for the liquid comprise, in general, separately attachable units which may be interchangeably used. In my present invention, I contemplate including the dispensing apparatus more or less as part of the container, which may be centrally assembled and distributed, wherever desired.

Other objects of my invention, including features embodied in my patents, reside in the association with containers for dispensing liquids, particularly liquids for dispensing subcutaneous, intravenous injections, of compact dispensing assemblies more or less forming part of the container, yet providing, in a simple and economical manner, the certainty and security of action of the more costly dispensing elements in my prior applications.

Such objects and advantages inherent in my construction will become apparent and will be more clearly pointed out as this description proceeds, and for this purpose I refer to the accompanying drawing, forming a part hereof, in which:

Figure 1 is a longitudinal sectional view of an embodiment of my invention, in which a unitary air filter and fluid conducting assembly may be associated with the sealing cap of the container;

Figure 2 is a section taken on the line 2—2 of Figure 1;

Figure 3 is a section taken on the line 3—3 of Figure 1;

Figure 4 is a section taken on the line 4—4 of Figure 1.

Referring to the drawing, the liquid dispensing device comprises a container C having a bottom 19a, in a form to provide a merchandising package of completely sealed fluid. (The container C is shown in its upright position in Fig. 1, as in the parent application, although the schematic

view of Figure 1 is directed to a generally inverted position of the device.) The container C is provided on an upper surface with a neck 6, which neck 6 is provided with a shoulder and a tapered portion 7, to which may be applied a screw cap 1a, for sealing the same. The screw cap 1a is provided with a centrally located orifice 1b, through which a portion of the air filter and fluid duct and tube assembly projects.

10 In this construction an insert in the form of a plug or stopper 8 is inserted and limited for projection into the interior of the neck 6 by tapering somewhat, so that it may be readily removed without any special instrumentalities. 15 This insert serves to support the air filter and fluid duct and tube assembly in which 9 is the fluid duct terminating outwardly in an opening 10 and is preferably formed with a beaded portion. The inner portion of the fluid duct 9 terminates at the interior of the container in an opening 11. A partition 12, secured to the tube 17 at an intermediate point, and a neck 13 define the air filter compartment 14, to which air may be conducted through the orifice 15 in the tube 17 open to the atmosphere, through the elongated air passage 16 within the tube 17, coaxial with and surrounding the fluid duct 9, previously mentioned.

20 The air tube 17 is preferably frictionally held 25 within the insert 8 in an orifice centrally formed therein. Where the ducts or tubes 9 and 16 are made of glass and the stopper 8 of rubber, frictional engagement between these members will be found sufficient. It will be understood, however, that the parts may be of metal, plastics, such as Bakelite, hard rubber, glass, as may be deemed expedient.

25 It will be seen that the air duct or tube 16 has 30 its lowermost end 18 considerably nearer the bottom 19 of the container than is the entrance 11 of the fluid duct 10.

The innermost portion of the tube 17 is closed, and is sealed at its approximate medial portion into the partition 12. Centrally of the air passage 16 there is provided an inwardly directed tube 19, which has its exit portion laterally extended into a side wall of the air tube 17 forming the opening 20, through which the air may escape through any liquid within the compartment 14 when the assembly is inverted. The air then escapes through the neck 13 and its extension 18.

With the construction thus provided, the entire assembly may be slipped into the neck of the bottle, after first filling the container C with the fluid to be dispensed, or the filling operation may

be conducted through the tube 9 by forced filling operations as described in my parent application. When sterile fluids are to be dispensed, it will be understood that the stopper 8 and the assembly carried thereby are to be thoroughly cleansed and sterilized before they are inserted in the neck of the container.

It will be understood that the opening 10 of the fluid duct 9 is provided with a closure tip 24 for sealing the contents of the container. When ready for use, the cap 7a is removed by unscrewing and the tip in the opening 10 likewise removed. A dispensing tube, preferably provided with pinch means to prevent premature flow of liquid, is then inserted over the beaded end 10 of the fluid duct 9.

The container is preferably filled with fluid in its upright position, and the fluid level extends approximately to the foremost part of the neck of the bottle. It is thus apparent that a portion of the fluid will seek its level within the chamber 14 of the air filtering device. Upon inversion of the container preparatory to the dispensing operation, a portion of the fluid within the container 14 will enter the smaller chamber 19, where it is trapped, and will serve to subject the incoming air to a thorough scrubbing action within the narrow confines of this inner chamber.

In operation, when the control means upon the dispensing tube adapted to be attached to the beaded opening 10 is released, the fluid within the container C will pass through the tube 9. It is to be noted that the opening 11 into the tube 10 is spaced from the lower edge of the stopper 8, so that when the container is in its inverted, dispensing position, any insoluble matter will separate out and will not lead through the opening 11, and the space between the opening 11 and the stopper acts as a sedimentation zone.

A constant flow and continuous accumulation of fluid to be dispensed will be assured by the admission of air through the air tube or air duct 15 passing upwardly (in the inverted position of the container) through elongated passage 16, downwardly through the narrow chamber 19 and the washing fluid contained therein, and will bubble upwardly through the washing fluid in the chamber 14 past the orifice 18 to the interior of the container. Thus it will be observed that, as the fluid leaves the duct 9, air enters into the space at the bottom of the bottle displaced by the fluid after it has been subjected to a thorough scrubbing action in passing through a circuitous path in the air washing assembly wherein any dust particles, lint or other impurities will be removed by the washing action of the fluid trapped therein.

It will be understood that in the operation of the device, the inversion of the container and the dispensing of the fluid leaves an area of reduced pressure within the container in the vicinity of the bottom 19a. Accordingly, the normal atmospheric pressure at the orifice 15 is greater than the pressures within the elongated air passage 16. As soon as the pinch means for the dispensing tube is released to permit the flow of liquid from the container, the air coming in through the air inlet 15 enters at a constant rate and substantially prevents the liquid within the passage 16 from flowing out. The retention of the portion 70 of liquid within the passage 16 is further aided by two well-known phenomena. The inlet 15 is relatively small in diameter and, therefore, the phenomena of skin resistance of materials, such as glass, and the surface tension of liquids fur-

ther aid in keeping the liquid within the passage 16. However, it is to be understood that most of the washing effect of the incoming air will be obtained within the chamber 19 and the chamber 14.

By providing a container and dispensing assembly of clear glass, the operation of the dispensing device may be observed, and the bubbling and washing action of the air as it passes through the assembly may be seen and the rate of flow and its regularity may be ascertained from the nature and character of the bubbles passing through the liquid within the chamber 14.

It will further be observed that by direct separation of the fluid in the dispensing assembly comprising the chambers 14, 19 and the air passage 16 from the interior of the container C, no contamination can occur of the fluid to be dispensed.

20 This form of construction will serve to retain the air filter compartments 14 and 19 filled with liquid, and the relationship between the orifice 20 and the tube 19 is such that the air cannot displace the liquid within the compartments but is given the opportunity for expansion, in the case of temperature changes, without causing the liquid within the compartment 14 to reenter the main portion of the container C, and without contaminating the liquid to be dispensed. The construction further provides an air filter and fluid duct assembly which need not be permanently assembled with the container but may be associated therewith when necessary for use, the cap 7a also serving as a means to retain the frictionally held plug in its position within the neck of the bottle.

It will be understood that while the cap 7a is shown provided with the orifice 7b, when merchandised in the sealed form, prior to the insertion of the plug 8, the container without the air filter and fluid conducting tube, may be sealed by a gasket fully covering the neck 6 of the container C and held in this position by the cap 7a.

A single tip or seal 24 (shown in dotted lines) 45 may serve to cover both the fluid outlet tube 9 and the air inlet orifice 15, after the container is filled with the fluid to be dispensed and before it is inverted, thus insuring the retention of the assembly in a facile manner.

50 It will be understood that the size of the fluid outlet 10 is related to the size of the air inlet 15 so that the rate of flow of liquid from the fluid duct will maintain a balanced condition, preventing the premature flow of fluid from the air passage 16 when the device is inverted.

It will thus be observed that I have provided a liquid dispensing device which may be merchandised as a complete assembly, with the fluids to be used, and any one desiring to dispense the fluid, for any purpose, need only be concerned with the sterilization of the connecting tube and hypodermic for injection, the remainder of the assembly having been previously sterilized and made in readiness at the centralized bottling and assembling point.

While I have emphasized the novelty of the construction, for purposes in the field of medicine, it will be understood that this device has a wider field of utility, which will be readily understood by those skilled in the art.

It will further be observed that while I have described my assembly as having particular utility by reason of the fact that it provides a device which may dispense fluids without contamination by the materials carried by air, thus effec-

tively filtering the air which is necessary for displacing the fluid which is being dispensed, the air passage provided for displacing the liquid also serves as a vent for filling purposes when the container is being filled, with the air filtering and dispensing assembly in position. This air duct permits sterilization of the container and of the liquid after filling and permits discharge of any entrained air, and capping to effect a vacuum sealing of the thus sterilized container and contents.

Having thus described my invention and illustrated its use, what I claim as new and desire to secure by Letters Patent is:

In a self-contained air filter and fluid dispensing assembly operable upon inversion and adapted to be inserted through the neck of a container housing liquid to be dispensed, an apertured

member inserted in the neck of the container, an air conducting tube and a fluid discharge tube coaxially disposed and forming an integral stem for suspending the assembly from said member 5 in the neck of said container, a fluid chamber within said container connected to said air conducting tube, a smaller air washing chamber within said fluid chamber, both of said chambers being adapted to trap portions of the liquid to be dispensed upon inversion of the container, said liquid portions serving as a washing fluid for incoming air, said air conducting tube, fluid discharge tube, fluid chamber and air washing chamber forming a unitary integral assembly 10 and providing a circuitous path for incoming air so that it receives a thorough wash before entering said container.

MARTIN C. SCHWAB.
